15 Claims. (Cl. 260—294.3)

1

This invention relates to quaternary ammonium salts of lower alkyl 4 - substituted - 2-(tertiary - aminoalkoxy)benzoates and to their preparation.

The quaternary ammonium salts of our invention have the general formula

where Z is nitro, amino, lower alkylamino or lower hydroxyalkylamino, X is a lower alkylene radical, NRR1 is a tertiary-amino radical, R2 is a lower alkyl radical, R4 is a lower alkyl radical or a benzyl radical and An is a non-toxic anion. These compounds of our invention have useful pharmacological properties, such as ganglionic blocking activity.

In the above general formula, the lower alkylene radical designated as X has preferably two to four carbon atoms and has its two free valence bonds on different carbon atoms. Thus, X includes such examples as

and the like. The tertiary-amino radical shown above as NRR1 comprehends dialkylamino radicals where R and R1 are lower alkyl groups, alike or different, and each alkyl group having one to six carbon atoms, such dialkylamino radicals including dimethylamino, diethylamino, ethylmethylamino, diisopropyl amino, ethyl - n - propylamino, di - n - butylamino, di-n-hexylamino, and the like. Further, the tertiary-amino radical designated as NRR1 encompasses saturated N-heteromonocyclic radicals having five to six ring atoms, illustrated by examples such as 1-piperidyl; (lower alkylated)-1-piperidyl such as 2-methyl-1-piperidyl, 3-ethyl-1-piperidyl, 4-methyl-1-piperidyl, 2,6-

dimethyl - 1 - piperidyl; 1 - pyrrolidyl; (lower alkylated) - 1 - pyrrolidyl such as 2-methyl-1-pyrrolidyl, 2,5 - dimethyl - 1 - pyrrolidyl; 4-morpholinyl; and the like. In the above formula, when Z stands for lower alkylamino, the lower alkyl radical, designated as R3 hereinbelow, has preferably one to six carbon atoms, including such radicals as methyl, ethyl, n-propyl, n-butyl, isobutyl, n-amyl, 2-amyl, n-hexyl, and the like. When Z represents lower hydroxyalkylamino, the lower hydroxyalkyl radical, designated as R3 hereinbelow, has preferably two to six carbon atoms, including radicals such as 2-hydroxyethyl, 2-hydroxypropyl, 3-hydroxypropyl, 3-hydroxy-2-methylpropyl, 3-hydroxy - 2,2 - dimethylpropyl, 2 - hydroxybutyl, 4 - hydroxybutyl, 3 - hydroxyamyl, 5-hydroxyamyl, 6-hydroxyhexyl, and the like. R4 when representing lower alkyl has preferably one to six carbon atoms, including such radicals as methyl, ethyl, n-propyl, n-butyl, isobutyl, n-amyl, n-hexyl, and the like. The non-toxic anion, designated above as An, which can be any anion, for instance chloride, bromide, iodide, sulfate, benzenesulfonate, para-toluenesulfonate, and the like, has no appreciable pharmacological activity of its own in the high dilutions at which the quaternary ammonium salts as a whole are effective. In particular, the anions contribute nothing to the ganglionic blocking activity which resides solely in the remainder of the molecule.

Thus, our invention comprehends quaternary ammonium salts of the above defined lower alkyl 4 - substituted - 2 - (tertiary - aminoalkoxy)benzoates, said salts being derived from lower alkyl or benzyl esters of an acid, either inorganic or organic, such esters having the formula R4-An and including methyl iodide, methyl bromide, ethyl chloride, ethyl bromide, ethyl sulfate, n-propyl iodide, benzyl chloride, methyl para-toluenesulfonate, ethyl para-toluenesulfonate, ethyl benzenesulfonate, and the like, the respective quaternary salts being the methiodides, methobromides, ethochlorides, ethobromides, ethosulfates, n-propiodides, benzo-

chlorides, metho-para-toluenesulfonates, etho-para-toluenesulfonates, ethobenzenesulfonates, and the like.

The parent lower alkyl 4 - substituted - 2 - (tertiary-aminoalkoxy)benzoates are disclosed and claimed in our copending application Serial Number 245,244, filed September 5, 1951, and they can be prepared preferably according to the procedure represented by the following series of equations where X, NRR₁, R₂ and R₃ have the meanings given hereinabove and halogen is chlorine, iodine or fluorine:

Thus, in step I, a lower alkyl 4-nitro-2-hydroxybenzoate (A) is converted into a lower alkyl 4 - nitro - 2 - (tertiary - aminoalkoxy)benzoate (C) by reaction with tertiary-aminoalkyl halide (B). In step II, the lower alkyl 4-nitro-2-(tertiary-aminoalkoxy)benzoate (C) is reduced to yield the corresponding lower alkyl 4-amino-2-(tertiary-aminoalkoxy)benzoate (D), which is then alkylated to form the corresponding lower alkyl 4-alkylamino- or 4-hydroxyalkylamino-2-(tertiary-aminoalkoxy)benzoate (E). A specific illustration of this series of reaction is the formation of ethyl 4-n-butylamino-2-(2-diethylaminoethoxy)benzoate by first reacting ethyl 4 - nitro - 2 - hydroxybenzoate, preferably in the form of an alkali metal salt, with a 2-diethylaminoethyl halide, preferably the chloride, to yield ethyl 4 - nitro - 2 - (2 - diethylaminoethoxy)benzoate, reducing this 4-nitro compound to yield the corresponding ethyl 4-amino - 2 - (2 - diethylaminoethoxy)benzoate and then alkylating this 4-amino compound to produce ethyl 4 - n - butylamino - 2 - (2 - diethylaminoethoxy)benzoate.

Step I is carried out preferably using a lower alkyl 4-nitro-2-hydroxybenzoate in the form of a metal salt, with a tertiary-aminoalkyl halide. Alternatively, step I can be carried out using a lower alkyl 4-nitro-2-hydroxybenzoate itself, however, with a resulting decrease in yield of the lower alkyl 4-nitro-2-(tertiary-aminoalkoxy)benzoate.

The reduction step II is carried out either by chemical methods or by catalytic hydrogenation. Suitable chemical reducing agents include iron and hydrochloric acid, ferrous sulfate and ammonia, tin and hydrochloric acid, sodium hydroxide, etc. In practicing our invention, we preferably used iron and hydrochloric acid. Catalysts suitable when catalytic hydrogenation is employed include Raney nickel, platinum, palladium or other catalysts generally effective to

catalyze hydrogenation of nitro groups to amino groups.

The alkylation of the lower alkyl 4-amino-2-(tertiary-aminoalkoxy)benzoates (D) to produce the related lower alkyl 4-alkylamino- or 4-hydroxyalkylamino-benzoates (step III) where R₃ has from three to six carbon atoms is preferably carried out by reductively alkylating the 4-amino compound with an alkanal or a hydroxyalkanal. Thus, this preferred method of alkylating the 4-amino benzoates (D) is by treating a mixture of a lower alkyl 4-amino-2-(tertiary-aminoalkoxy)benzoate and an alkanal or hydroxyalkanal, having from three to six carbon atoms, in a reducing medium. This reduction is carried out either by chemical methods or by catalytic hydrogenation. Illustrative of this reductive alkylation step is the formation of n-propyl 4-n-amylamino-2-[2-(1-piperidyl)ethoxy]benzoate or n-propyl 4-(5-hydroxyamylamino)-2-[2-(1-piperidyl)ethoxy]benzoate by treating a mixture of the corresponding n-propyl 4-amino-2-[2-(1-piperidyl)ethoxy]benzoate with pentanal (valeraldehyde) or 5-hydroxypentanal, respectively, with chemical reducing agents, such as zinc dust and acetic acid, iron and acetic acid, iron and hydrochloric acid, etc., or with hydrogen under pressure using catalysts such as platinum, palladium, Raney nickel or other catalysts generally effective in reductive alkylations using alkanals and hydroxyalkanals.

Alternatively, the alkylation step III can be carried out directly by heating a lower alkyl 4-amino-2-(tertiary-aminoalkoxy)benzoate (D) with an alkylating agent such as methyl iodide, ethyl bromide, n-propyl bromide, isobutyl iodide, 2-hydroxyethyl bromide, 4-hydroxybutyl chloride, and the like, in the presence of a hydrogen halide acceptor, e. g., sodium bicarbonate, potassium carbonate, etc. Thus, such treatment of ethyl 4-amino-2-(3-diethylaminopropoxy)benzoate with methyl iodide, ethyl bromide or 2-hydroxyethyl bromide yields, respectively, ethyl 4-methylamino - 2 - (3 - diethylaminopropoxy)benzoate, ethyl 4-ethylamino-2-(3-diethylaminopropoxy)benzoate or ethyl 4-(2-hydroxyethylamino) - 2 - (3 - diethylaminopropoxy)benzoate. Yields of the resulting lower alkyl 4-alkylamino- and 4-hydroxyalkylamino-2-(tertiary-aminoalkoxy)benzoates obtained by this method are lower than those obtained by the foregoing described reductive alkylation procedure due to quaternary formation in this reaction.

Step I can also be carried out stepwise, that is, by first haloalkylating a lower alkyl 4-nitro-2-hydroxybenzoate (A) to form a lower alkyl 4-nitro-2-(haloalkoxy)benzoate which is then treated with a secondary amine having the formula HNRR₁. The first step can be accomplished by treating either a lower alkyl 4-nitro-2-hydroxybenzoate or a metal salt thereof with a haloalkylating agent such as a haloalkyl para-toluenesulfonate, haloalkyl benzenesulfonate, dihaloalkane, etc. As illustrations of this stepwise procedure, ethyl 4-nitro-2-hydroxybenzoate is haloalkylated by treating its sodium salt with 2-chloroethyl para-toluenesulfonate to form ethyl 4-nitro-2-(2-chloroethoxy)benzoate which then is treated with diethylamine or piperidine to form ethyl 4-nitro-2-(2-diethylaminoethoxy)benzoate or ethyl 4-nitro-2-[2-(1-piperidyl)ethoxy]benzoate, respectively.

The quaternary ammonium salts of our present invention are prepared according to the process as illustrated for the methiodides by the fol-

lowing series of equations where X, NRR₁, R₂ and R₃ are defined as above:

In step IV, a lower alkyl 4-nitro-2-(tertiary-aminoalkoxy)benzoate (C) is treated with methyl iodide to yield the corresponding lower alkyl 4-nitro-2-(tertiary-aminoalkoxy)benzoate methiodide (F). In step V, the 4-nitro methiodide (F) is reduced to yield the corresponding lower alkyl 4-amino-2-(tertiary-aminoalkoxy)benzoate methiodide (G), which, in step VI, is alkylated to produce the corresponding lower alkyl 4-alkylamino- or 4-hydroxyalkylamino-2-(tertiary-aminoalkoxy)benzoate methiodide (H). As a specific illustration of this series of reactions, ethyl 4-nitro-2-(2-diethylaminoethoxy)benzoate is treated with methyl iodide to form ethyl 4-nitro-2-(2-diethylaminoethoxy)benzoate methiodide, which is then reduced to yield the corresponding ethyl 4-amino-2-(2-diethylaminoethoxy)benzoate methiodide, which, in turn, is alkylated to yield ethyl 4-n-butylamino-2-(2-diethylaminoethoxy)benzoate methiodide.

When, in step IV, other lower alkyl or benzyl esters of an acid is substituted for methyl iodide, the corresponding 4-nitro (F), 4-amino (G) and 4-substituted-amino (H) quaternary salts are formed. Other lower alkyl and benzyl esters that are suitable include those shown hereinabove.

The reduction step V is carried out preferably by catalytic hydrogenation using such catalysts as Raney nickel, platinum, palladium or other catalysts generally effective to catalyze nitro groups to amino groups. Alternatively, but less desirably, this reduction step can be carried out by chemical methods. Suitable chemical reducing agents include iron and a hydrohalic acid, tin and a hydrohalic acid, etc.

The alkylation step VI to produce the lower alkyl 4-alkylamino- or 4-hydroxyalkylamino-2-(tertiary-aminoalkoxy)benzoate quaternary salts where the alkyl or hydroxyalkyl radical, designated as R₃, has from three to six carbon atoms, is preferably carried out by reductively alkylating the corresponding 4-amino quaternary salts with an alkanal or a hydroxyalkanal having from three to six carbon atoms. This reduction is carried out preferably by catalytic hydrogenation using catalysts such as platinum, palladium, Raney nickel or other catalysts generally effective in reduction alkylation using alkanals and hydroxy-alkanals. Alternatively, this reductive alkylation procedure can be carried out, but with lower yields, by chemical methods using chemical reducing agents such as zinc and acetic acid, etc.

Alternatively, but less desirably, the alkylation

step VI can be done directly by heating a lower alkyl 4-amino-2-(tertiary-aminoalkoxy)benzoate quaternary salt with an alkylating agent such as methyl iodide, ethyl bromide, n-propyl bromide, isobutyl iodide, 2-hydroxyethyl bromide, 4-hydroxybutyl chloride, and the like, in the presence of a hydrogen halide acceptor, e. g., sodium bicarbonate, potassium carbonate. Thus, such treatment of ethyl 4-amino-2-(3-diethylamino-propoxy)benzoate methiodide with methyl iodide, ethyl bromide or 2-hydroxyethyl bromide yields, respectively, ethyl 4-methylamino-2-(3-diethylaminoalkoxy)benzoate methiodide, ethyl 4-ethylamino-2-(3-diethylaminoalkoxy)benzoate methiodide or ethyl 4-(2-hydroxyethylamino)-2-(3-diethylaminoalkoxy)benzoate methiodide. Yields of the resulting lower alkyl 4-alkylamino- and 4-hydroxyalkylamino-2-(tertiary-aminoalkoxy)benzoate quaternary salts obtained by this method are lower than those obtained by the foregoing described reductive alkylation procedure due to overalkylation and anion exchange reactions.

The lower alkyl 4-alkylamino- and 4-hydroxy-alkylamino-2-(tertiary-aminoalkoxy)benzoate quaternary salts can also be prepared, but less preferably, by treating a lower alkyl 4-alkylamino- or 4-hydroxyalkylamino-2-(tertiary-aminoalkoxy)benzoate, designated above as (E), with an alkyl or benzyl ester of an inorganic or organic acid, said esters being of the type described above. Thus, treatment of ethyl 4-n-amylamino- or 4-(5-hydroxyamylamino)-2-[2-(2,6-dimethyl-1-piperidyl)ethoxy]benzoate with methyl iodide results in the formation of ethyl 4-n-amylamino-2-[2-(2,6-dimethyl-1-piperidyl)ethoxy]benzoate methiodide or ethyl 4-(5-hydroxyamylamino)-2-[2-(2,6-dimethyl-1-piperidyl)ethoxy]benzoate methiodide. Using benzyl chloride in place of methyl iodide yields ethyl 4-n-amylamino-2-[2-(2,6-dimethyl-1-piperidyl)ethoxy]benzoate benzochloride or ethyl 4-(5-hydroxyamylamino)-2-[2-(2,6-dimethyl-1-piperidyl)ethoxy]benzoate benzochloride, respectively.

Similarly, the lower alkyl 4-amino-2-(tertiary-aminoalkoxy)benzoate quaternary salts can be prepared, but less preferably, by treating, preferably at room temperature, the corresponding lower alkyl 4-amino-2-(tertiary-aminoalkoxy)-benzoates designated above as (D), with an alkyl or benzyl ester of an inorganic or organic acid of the type described hereinabove. Thus, treatment of methyl 4-amino-2-[3-(1-pyrrolidyl)propoxy]benzoate with methyl iodide or benzyl chloride results in the formation of methyl 4-amino-2-[3-(1-pyrrolidyl)propoxy]benzoate methiodide or methyl 4-amino-2-[3-(1-pyrrolidyl)propoxy]benzoate benzochloride, respectively. This mode of preparation is not as desirable as the foregoing described method of reducing the corresponding lower alkyl 4-nitro-2-(tertiary-aminoalkoxy)benzoate quaternary ammonium salts since here some alkylation of the 4-amino radical might result, as a competing reaction. Conditions more favorable for alkylation of the 4-amino radical were presented above, namely, heating the mixture of reactants and doing so in the presence of a hydrogen halide acceptor.

Specific embodiments of our invention are illustrated by the following examples.

(1) *Lower alkyl 4-nitro-2-(tertiary-aminoalkoxy)benzoates*

Preparation of the lower alkyl 4-nitro-2-(tertiary-aminoalkoxy)benzoates is illustrated by the

following alternative procedures, all of which involve alkylation of a lower alkyl 4-nitro-2-hydroxybenzoate or a metal salt thereof with a tertiary-aminoalkyl halide, or, stepwise, with a haloalkylating agent such as a haloalkyl para-toluenesulfonate to produce a lower alkyl 4-nitro-2-(haloalkoxy)benzoate which is then treated with a secondary amine to form the desired lower alkyl 4-nitro-2-(tertiary-aminoalkoxy)benzoate.

Ethyl 4-nitro-2-(2-diethylaminoethoxy)benzoate was prepared as follows: To a stirred refluxing solution of 42.2 g. of ethyl 4-nitro-2-hydroxybenzoate in 1000 ml. of absolute alcohol was added slowly a solution of 4.6 g. of sodium in 500 ml. of absolute ethanol. To the resulting deep red solution was added, with stirring over a period of about twenty minutes, 27.1 g. of 2-diethylaminoethyl chloride and the resulting mixture was refluxed for about three hours. An additional 5 g. of 2-diethylaminoethyl chloride was then added and refluxing continued for an additional thirty minutes. The reaction mixture was cooled in ice, filtered, and the filtrate taken to dryness in vacuo. The residue was taken up in 500 ml. of ethyl acetate, the resulting solution filtered and the filtrate taken to dryness, yielding ethyl 4-nitro-2-(2-diethylaminoethoxy)benzoate. This compound was converted into its hydrochloride addition salt by dissolving it in a small amount of ethyl acetate and treating the solution with an excess of 20% ethereal hydrogen chloride solution. The resulting precipitate of ethyl 4-nitro-2-(2-diethylaminoethoxy)benzoate hydrochloride was collected and recrystallized twice from isopropanol, yielding 45.5 g. of purified product, M. P. 144.4-145.2° C. (cor.).

Anal.—Calcd. for $C_{15}H_{22}N_2O_5 \cdot HCl$: C, 51.94; H, 6.40; Cl, 10.22. Found: C, 52.08; H, 6.48; Cl, 10.12.

Ethyl 4-nitro-2-(2-diethylaminoethoxy)benzoate was also prepared stepwise as follows: A mixture of 84.4 g. of ethyl 4-nitro-2-hydroxybenzoate, 60.8 g. of powdered anhydrous potassium carbonate and 2000 ml. of meta-xylene was refluxed with stirring under a water trap until no more water was collected (three hours). The water trap was removed and 112.7 g. of 2-chloroethyl para-toluenesulfonate was added in one portion. Refluxing and stirring were continued for an additional nineteen hours. The mixture was filtered while hot and the filter-cake was washed with hot toluene. The combined filtrate and washings were evaporated to dryness in vacuo, yielding a cream-colored solid as residue. Several recrystallizations of this solid from methanol and from n-pentane gave a 60% yield of ethyl 4-nitro-2-(2-chloroethoxy)benzoate as pale yellow platelets, M. P. 56.6-57.2° C. (cor.).

Anal.—Calcd. for $C_{11}H_{12}ClNO_5$: Cl, 12.96. Found: Cl, 12.62.

On heating a mixture of ethyl 4-nitro-2-(2-chloroethoxy)benzoate, diethylamine, sodium iodide and absolute ethanol, there was obtained, in only a fair yield, ethyl 4-nitro-2-(2-diethylaminoethoxy)benzoate. Following this same procedure but using dimethylamine or 2-methylpiperidine in place of diethylamine, there is obtained, ethyl 4-nitro-2-(2-dimethylaminoethoxy)benzoate or ethyl 4-nitro-2-[2-(2-methyl-1-piperidyl)ethoxy]benzoate, respectively.

Ethyl 4-nitro-2-[3-(1-piperidyl)propoxy]benzoate was prepared as follows: To a stirred refluxing solution of 84.4 g. of ethyl 4-nitro-2-

hydroxybenzoate in 1500 ml. of absolute ethanol was added in a fine stream a solution of 9.2 g. of sodium in 500 ml. of absolute ethanol. To the resulting solution was added dropwise over a period of fifteen minutes 65 g. of 3-(1-piperidyl)propyl chloride and the resulting solution was refluxed for twenty-four hours. The sodium chloride was filtered off and washed with ethyl acetate. The combined filtrate and washings were taken down to dryness under reduced pressure yielding a mixture of an oily residue and a small amount of a red solid. To this mixture was added 2 liters of ether and the insoluble red solid was filtered off. The filtrate was evaporated to dryness under reduced pressure, yielding, as an oily material, ethyl 4-nitro-2-[3-(1-piperidyl)propoxy]benzoate. This ester was converted into its hydrochloride salt by dissolving it in a little ethyl acetate and adding to the solution an excess of ethanolic hydrogen chloride. The solid hydrochloride separated slowly. The mixture was diluted with absolute ether, cooled, and the precipitate was collected and washed with absolute ether. The precipitate was recrystallized three times from isopropanol, yielding, as pale yellow needles, ethyl 4-nitro-2-[3-(1-piperidyl)propoxy]benzoate hydrochloride, M. P. 160.4-161.6° C. (cor.).

Anal.—Calcd. for $C_{17}H_{24}N_2O_5 \cdot HCl$: N_D, 7.52; Cl, 9.51. Found: N_D, 7.37; Cl, 9.33.

N_D stands for total nitrogen as determined by the Dumas method.

n-Butyl 4-nitro-2-(2-diethylaminoethoxy)benzoate was prepared as follows: To a stirred refluxing solution of 9.2 g. of sodium in 2000 ml. of n-butanol was added 95.7 g. of n-butyl 4-nitro-2-hydroxybenzoate. The red insoluble sodium phenolate separated immediately. After addition had been complete, refluxing was continued for an additional ten minutes, and then 54.2 g. of 2-diethylaminoethyl chloride was added dropwise over a period of about twenty minutes. When the addition had been completed, the color had already changed from a deep red to a pale orange-yellow. The reaction mixture was then refluxed for five hours, cooled and filtered. The filtrate was taken down to dryness under reduced pressure yielding an oily residue and a small amount of red solid. This mixture was treated with 2500 ml. of absolute ether, and the red solid was filtered off. The filtrate was taken down to dryness under reduced pressure, yielding, as an oil, the product, n-butyl 4-nitro-2-(2-diethylaminoethoxy)benzoate. This ester was converted into its hydrochloride addition salt by dissolving it in a little absolute ether and treating the solution with an excess of ethereal hydrogen chloride. A pale cream-coloured solid separated. The mixture was cooled and the solid was collected and washed with absolute ether. Three recrystallizations of this solid from ethyl acetate yielded, as pale yellow needles, n-butyl 4-nitro-2-(2-diethylaminoethoxy)benzoate hydrochloride, M. P. 117.6-118.6° C. (cor.).

Anal.—Calcd. for $C_{17}H_{24}N_2O_5 \cdot HCl$: N_D, 7.47; Cl, 9.46. Found: N_D, 7.66; Cl, 9.44.

Ethyl 4-nitro-2-(2-dimethylaminoethoxy)benzoate was prepared as follows: To a solution of 126.6 g. of ethyl 4-nitro-2-hydroxybenzoate in 1000 ml. of absolute ethanol was added a solution of 13.8 g. of sodium in 500 ml. of absolute ethanol. The ethanol was then removed by distillation while simultaneously adding toluene (1000 ml.). To the resulting bright red suspension of the sodium salt of ethyl 4-nitro-2-hy-

droxybenzoate in toluene was added 66.3 g. of 2-dimethylaminoethyl chloride and the mixture was refluxed with stirring for forty-eight hours. The mixture was filtered while hot and the filter-cake was washed with hot toluene. The combined filtrate and washings were evaporated in vacuo, leaving a quantitative yield of ethyl 4-nitro-2-(2-dimethylaminoethoxy)benzoate, as in oil. Treatment of an ethyl acetate solution of this compound with an excess of 20% ethereal hydrogen chloride gave a gummy precipitate, which crystallized from isopropanol in pale yellow needles, M. P. 202.2-202.6° C. (cor.). This product was ethyl 4-nitro-2-(2-dimethylaminoethoxy)benzoate hydrochloride.

Anal.—Calcd. for $C_{13}H_{18}N_2O_5HCl$: N, 8.79; Cl, 11.12. Found: N, 8.56; Cl, 11.10.

Additional lower alkyl 4-nitro-2-(tertiary-aminoalkoxy)benzoates, in the form of their hydrochlorides, prepared according to the above described procedures are given in Table I'.

aminoalkoxy)benzoates, as described hereinabove. Illustrative of this reduction are the following examples.

5 Ethyl 4-amino-2-(2-diethylaminoethoxy)benzoate was prepared as follows: To a hot vigorously stirred mixture of 33.6 g. of powdered iron, 1 ml. of concentrated hydrochloric acid and 200 ml. of 50% aqueous ethanol was added slowly, over a period of about ten minutes, 35.7 g. of ethyl 4-nitro-2-(2-diethylaminoethoxy)benzoate hydrochloride. The resulting mixture was heated with stirring for another thirty minutes, after which an excess of solid sodium bicarbonate (about 15 g.) was added. The mixture was stirred for an additional ten minutes and then filtered through a filter aid which was subsequently washed with hot ethanol. The combined filtrate and washings were concentrated by distilling in vacuo, thereby yielding an oily residue which was taken up with ethyl acetate. The ethyl acetate was dried over anhydrous calcium

• Nitro nitrogen (N₂O₂) as determined by titration with standard titanous chloride in glacial acetic acid solution.

Additional lower alkyl 4-nitro-2-(tertiary-aminoalkoxy)benzoates which can be prepared according to the foregoing procedures include the following: ethyl 4-nitro-2-(2-dimethylamino-1-propoxy)benzoate; isobutyl 4-nitro-2-[3-(1-pyrrolidyl)propoxy]benzoate; ethyl 4-nitro-2-[2-(2,5-dimethyl-1-pyrrolidyl)ethoxy]benzoate; methyl 4-nitro-2-(4-dimethylaminobutoxy)benzoate; n-propyl 4-nitro-2-[2-(di-n-butylamino)ethoxy]benzoate; n-butyl 4-nitro-2-[3-(4-methyl-1-piperidyl)propoxy]benzoate; n-hexyl 4-nitro-2-[2-(3-ethyl-1-piperidyl)ethoxy]benzoate; n-amyl 4-nitro-2-[3-(2-methyl-1-pyrrolidyl)propoxy]benzoate; and the like.

(2) Lower alkyl 4-amino-2-(tertiary-aminoalkoxy)benzoates

These compounds are prepared by reduction of the corresponding lower alkyl 4-nitro-2-(tertiary-

60 sulfate and taken to dryness in vacuo yielding, as a pale orange, slightly viscous oil, 27.4 g. of the product, ethyl 4-amino-2-(2-diethylaminoethoxy)benzoate.

Alternatively, the foregoing preparation can be carried out using ethyl 4-nitro-2-(2-diethylaminoethoxy)benzoate in place of ethyl 4-nitro-2-(2-diethylaminoethoxy)benzoate hydrochloride.

70 The preparation of ethyl 4-amino-2-(2-diethylaminoethoxy)benzoate is in the form of its monohydrochloride salt was accomplished as follows: To a solution of 12.0 g. of ethyl 4-amino-2-(2-diethylaminoethoxy)benzoate dissolved in 50 ml. of absolute ethanol was added 8.50 ml. of an ethanolic solution of hydrogen chloride (0.1843 g./ml.; enough HCl to produce the monohydrochloride). The solution was mixed well, taken to dryness in vacuo, ethyl acetate added and re-

11

moved in vacuo, and the remaining residue dissolved in a small amount of isopropanol. To this solution was added a small amount of ethyl acetate and ether, just enough to produce turbidity, whereupon spontaneous crystallization resulted. The mixture was then diluted with ether, cooled in ice and the precipitate collected. Two recrystallizations from this precipitate from acetone-ethyl acetate yielded, as rosettes of white prisms, ethyl 4-amino-2-(2-diethylaminoethoxy)benzoate monohydrochloride, M. P. 134-135° C.

Anal.—Calcd. for $C_{15}H_{24}N_2O_3 \cdot HCl$: Cl, 11.19. Found: Cl, 11.20.

The dihydrochloride salt of the above 4-amino benzoate was prepared by dissolving it in ethyl acetate and treating the solution with an excess of ethereal hydrogen chloride. The mobile colorless oil which separated crystallized readily when triturated. The solid was filtered, washed well with ethyl acetate and recrystallized twice from absolute ethanol-ethyl acetate. There was thus obtained ethyl 4-amino-2-(2-diethylaminoethoxy)benzoate dihydrochloride, M. P. 173.6-173.9° C. (cor.) [dried three days at 50° C.]

Anal.—Calcd. for $C_{15}H_{24}N_2O_3 \cdot 2HCl$: C, 50.99; H, 7.42; Cl, 20.07. Found: C, 51.14; H, 7.36; Cl, 19.90.

Ethyl 4-amino-2-(2-diethylaminoethoxy)benzoate was converted into its phosphoric acid addition salts as follows: A solution of the ester in absolute ethanol was treated with a molar equivalent of 85% phosphoric acid in absolute ethanolic solution. The precipitated crystalline phosphate was collected and recrystallized four times from 95% ethanol, yielding ethyl 4-amino-2-(2-diethylaminoethoxy)benzoate phosphate, M.P. 168.7-169.6° C. (cor.).

Anal.—Calcd. for $C_{15}H_{27}N_2O_5P$: H_3PO_4 , 25.91; Nd, 7.40. Found: H_3PO_4 , 25.30; Nd, 7.41.

n-Butyl 4-amino-2-(2-diethylaminoethoxy)benzoate was prepared as follows: A stirred mixture of 71.5 g. of powdered iron, 300 ml. of ethanol, 75 ml. of water and 1 ml. of concentrated hydrochloric acid was brought to a boil. Heat was removed and 80.0 g. of n-butyl 4-nitro-2-(2-diethylaminoethoxy)benzoate hydrochloride was added portion-wise at such a rate as to maintain gentle boiling. After addition of the nitro compound had been completed, the reaction mixture was refluxed with stirring for thirty minutes. Then an excess of sodium bicarbonate (about 20 g.) was cautiously added and refluxing and stirring were continued for an additional ten minutes. The reaction mixture was filtered hot and the filtrate was concentrated in vacuo to remove all the ethanol. The product, which separated as distinct layer, was extracted with ethyl acetate. The ethyl acetate solution was dried over anhydrous calcium sulfate and concentrated in vacuo to yield, as a straw colored oil, n-butyl 4-amino-2-(2-diethylaminoethoxy)benzoate. This ester was converted into its phosphoric acid addition salt as follows: To a hot solution of 46 g. of n-butyl 4-amino-2-(2-diethylaminoethoxy)benzoate dissolved in a minimum quantity of hot absolute ethanol was added a hot ethanolic solution of 17.2 g. of 85% phosphoric acid. A white solid readily separated from the hot solution, which was diluted with ethyl acetate, cooled and filtered. The solid was recrystallized several times from absolute ethanol containing a small quantity of water, thereby yielding, as rosettes of white needles, n-butyl 4-amino-2-(2-diethylaminoethoxy)benzoate phosphate, M.P. 154.5-155.5° C. (cor.).

12

Anal.—Calcd. for $C_{17}H_{28}N_2O_3 \cdot H_3PO_4$: Nd, 6.88; H_3PO_4 , 24.12. Found: Nd, 7.10; H_3PO_4 , 24.15.

Ethyl 4-amino-2-[3-(1-piperidyl)propoxy]benzoate was prepared according to the procedure described above for the preparation of n-butyl 4-amino-2-(2-diethylaminoethoxy)benzoate but using 67.2 g. of powdered iron, 400 ml. of ethanol, 100 ml. of water, 1 ml. of concentrated hydrochloric acid, 76 g. of ethyl 4-nitro-2-[3-(1-piperidyl)propoxy]benzoate hydrochloride and about 60 g. of sodium bicarbonate. Vacuum evaporation of the ethyl acetate extract yielded a solid product. This solid when recrystallized from ethanol yielded, as white needles, ethyl 4-amino-2-[3-(1-piperidyl)propoxy]benzoate, M.P. 109.2-110.1° C. (cor.).

Anal.—Calcd. for $C_{17}H_{26}N_2O_3$: Nd, 9.14. Found: Nd, 8.90.

Ethyl 4-amino-2-[3-(1-piperidyl)propoxy]benzoate phosphate, prepared as above, melted at 160.2-161.6° C. (cor.) when recrystallized several times from absolute ethanol.

Anal.—Calcd. for $C_{17}H_{26}N_2O_3 \cdot H_3PO_4$: Nd, 6.93; H_3PO_4 , 24.22. Found: Nd, 6.83; H_3PO_4 , 24.37.

Methyl 4-amino-2-[2-(4-morpholinyl)ethoxy]benzoate was prepared according to the foregoing procedures but using 13.15 g. of powdered iron, 1 ml. of concentrated hydrochloric acid, 400 ml. of 75% aqueous methanol and 13.6 g. of methyl 4-nitro-2-[2-(4-morpholinyl)ethoxy]benzoate hydrochloride. The product, methyl 4-amino-2-[2-(4-morpholinyl)ethoxy]benzoate, was obtained as an oil. This ester was converted into its diphosphate as follows: A solution of 9.5 g. of methyl 4-amino-2-[2-(4-morpholinyl)ethoxy]benzoate in 25 ml. of methanol was treated with a solution of 3.19 g. of 85% phosphoric acid in 25 ml. of methanol, whereupon there separated immediately a gummy material. Ethyl acetate was added to the mixture and the precipitated material was triturated while warming. The supernatant liquid was decanted and the gummy material was triturated several times with warm absolute ethanol, whereupon solidification finally resulted. The solid was filtered and recrystallized by suspending it in hot absolute ethanol and adding hot water dropwise until the solution became clear, treating the solution with decolorizing charcoal, filtering and allowing the filtrate to cool. The finely divided white salt that separated was collected and dried in vacuo at 100° C., yielding 5.5 g. of methyl 4-amino-2-[2-(4-morpholinyl)ethoxy]benzoate diphosphate, M.P. 151.3-152.1° C. (cor.).

Anal.—Calcd. for $C_{14}H_{20}N_2O_4 \cdot 2H_3PO_4$: Nd, 5.88; $2H_3PO_4$, 41.16. Found: Nd, 5.96; $2H_3PO_4$, 40.85.

The foregoing reductions of the lower alkyl 4-nitro-2-(tertiary-aminoalkoxy)benzoates to yield the corresponding 4-amino benzoates can be carried out by catalytic hydrogenation as illustrated by the following general preparation: Ten grams of the lower alkyl 4-nitro-2-(tertiary-aminoalkoxy)benzoate in 150 ml. of ethanol is hydrogenated using 50 lbs. pressure of hydrogen at 25° C. in the presence of 2 g. of Raney nickel. After the rapid exothermic reaction, the catalyst is filtered off and the filtrate evaporated to dryness. The resulting residue is dissolved in absolute ethanol and is treated with a solution of 85% phosphoric acid in absolute ethanol to yield the corresponding lower alkyl 4-amino-2-(tertiary-aminoalkoxy)benzoate phosphate.

Additional lower alkyl 4-amino-2-(tertiary-aminoalkoxy)benzoates, in the form of their

monophosphate salts, prepared according to the above procedures are given in Table II.

Additional lower alkyl 4-amino-2-(tertiary-aminoalkoxy)benzoates which can be prepared according to the foregoing procedures include the following: ethyl 4-amino-2-(2-dimethylamino-1-propoxy)benzoate; isobutyl 4-amino-2-[3-(1-pyrrolidyl)propoxy]benzoate; ethyl 4-amino-2-[2-(2,5-dimethyl-1-pyrrolidyl)ethoxy]benzoate; methyl 4-amino-2-(4-dimethylaminobutoxy)benzoate; n-propyl 4-amino-2-[2-(di-n-butylamino)ethoxy]benzoate; n-butyl 4-amino-2-[3-(4-methyl-1-piperidyl)propoxy]benzoate; n-hexyl 4-amino-2-[2-(3-ethyl-1-piperidyl)ethoxy]benzoate; n-amyl 4-amino-2-[3-(2-methyl-1-pyrrolidyl)propoxy]benzoate; and the like.

(3) Lower alkyl 4-alkylamino- and 4-hydroxy-alkylamino-2-(tertiary-aminoalkoxy)benzoates

These compounds are produced by alkylation of the corresponding lower alkyl 4-amino-2-(tertiary-aminoalkoxy)benzoates described above. This alkylation is run preferably by reductive alkylation procedures as illustrated in the following examples.

Ethyl 4-n-butylamino-2-(2-diethylaminoethoxy)benzoate was prepared as follows: To a hot stirred mixture of 26.0 g. of ethyl 4-amino-2-(2-diethylaminoethoxy)benzoate, 24.1 g. of zinc dust, 22.6 g. of glacial acetic acid and 450 ml. of dry benzene was added 8.0 g. of n-butanal (n-butyaldehyde) dissolved in 50 ml. of dry benzene over a fifteen minute period. After the mixture had been stirred for one hour, an additional 1 ml. of n-butanal was added and stirring continued for an additional fifteen minutes. The zinc acetate was filtered off and washed with hot dilute acetic acid and benzene. The cooled filtrate was made basic to litmus with concentrated ammonium hydroxide, the benzene layer was separated and the aqueous solution was extracted three

times with benzene. After the combined benzene layer and extracts had been dried over anhydrous

calcium sulfate, the benzene was removed by distilling in vacuo, yielding, as a straw colored oil, ethyl 4-n-butylamino-2-(2-diethylaminoethoxy)benzoate. This ester was converted into its monohydrochloride salt as follows: Eleven grams of the ester was dissolved in ethyl acetate and was treated with an excess of 20% by weight of ethanolic hydrogen chloride, whereupon a gummy material separated immediately. The supernatant liquid was decanted from the gum and the latter was triturated twice with warm ethyl acetate. The gummy material was then dissolved in a minimum amount of hot ethanol, 12 g. of ethyl 4-n-butylamino-2-(2-diethylaminoethoxy)benzoate was added and the solution was cooled. Absolute ether was then added to turbidity, whereupon a cream colored crystalline precipitate separated. The mixture was diluted to about 500 ml. with absolute ether. The precipitate was collected and recrystallized once from absolute ethanol-absolute ether with decolorization, using decolorizing charcoal, and a second time, with decolorization, from ethanol-ethyl acetate. There was thus obtained ethyl 4-n-butylamino-2-(2-diethylaminoethoxy)benzoate hydrochloride, M. P. 160.5-161.8° C. (cor.).

Anal.—Calcd. for C₁₉H₃₂N₂O₃.HCl: N_D, 7.51; Cl, 9.50. Found: N_D, 7.36; Cl, 9.45.

When the above procedure is followed but using n-propanal, n-pentanal and n-hexanal, in place of n-butanal, the resulting products, in the form of their monohydrochlorides, are ethyl 4-n-propylamino-2-(2-diethylaminoethoxy)benzoate, ethyl 4-n-amylamino-2-(2-diethylaminoethoxy)benzoate and ethyl 4-n-hexylamino-2-(2-diethylaminoethoxy)benzoate, respectively.

When the above procedure is followed but using, in place of ethyl 4-amino-2-(2-diethylaminoethoxy)benzoate, methyl 4-amino-2-[3-(1-

piperidyl)propoxy]benzoate, n-propyl 4-amino-2-[2-(2,6-dimethyl-1-piperidyl)ethoxy]benzoate, n-butyl 4-amino-2-[2-(2-methyl-1-piperidyl)ethoxy]benzoate or ethyl 4-amino-2-[2-(4-morpholinyl)ethoxy]benzoate, there is obtained, in the form of their monohydrochlorides, methyl 4-n-butylamino-2-[3-(1-piperidyl)propoxy]benzoate, n-propyl 4-n-butylamino-2-[2-(2,6-dimethyl-1-piperidyl)ethoxy]benzoate, n-butyl 4-n-butylamino-2-[2-(2-methyl-1-piperidyl)ethoxy]benzoate or ethyl 4-n-butylamino-2-[2-(4-morpholinyl)ethoxy]benzoate, respectively.

Ethyl 4-(5-hydroxyamylamino)-2-(2-diethylaminoethoxy)benzoate was obtained, as an oil, following the above procedure but using 26.0 g. of ethyl 4-amino-2-diethylaminoethoxybenzoate, 11.3 g. of 5-hydroxypentanal, 24.1 g. of zinc dust, 22.6 g. of glacial acetic acid and 500 ml. of dry benzene. Ethyl 4-(5-hydroxyamylamino)-2-(2-diethylaminoethoxy)benzoate monohydrochloride, M. P. 132.2-133.4° C. (cor.) was obtained following the procedure above for preparing ethyl 4-n-butylamino-2-(2-diethylaminoethoxy)benzoate monohydrochloride.

Anal.—Calcd. for $C_{20}H_{34}N_2O_4 \cdot HCl$: N_D, 6.95; Cl, 8.79. Found: N_D, 7.07; Cl, 9.05.

When the above procedure was followed but using, in place of ethyl 4-amino-2-(2-diethylaminoethoxy)benzoate, n-propyl 4-amino-2-(2-diethylaminoethoxy)benzoate and ethyl 4-amino-2-[2-(2,6-dimethyl-1-piperidyl)ethoxy]benzoate, there was obtained, as oils, n-propyl 4-(5-hydroxyamylamino)-2-(2-diethylaminoethoxy)benzoate and ethyl 4-(5-hydroxyamylamino)-2-[2-(2,6-dimethyl-1-piperidyl)ethoxy]benzoate, respectively.

When the above procedure is followed but using, in place of 5-hydroxypentanal, 3-hydroxypropanol, 4-hydroxybutanal, 3-hydroxybutanal or 6-hydroxyhexanal, there is obtained, in the form of their monohydrochlorides, ethyl 4-(3-hydroxypropylamino)-2-(2-diethylaminoethoxy)benzoate, ethyl 4-(4-hydroxybutylamino)-2-(2-diethylaminoethoxy)benzoate, ethyl 4-(3-hydroxybutylamino)-2-(2-diethylaminoethoxy)benzoate or ethyl 4-(6-hydroxyhexylamino)-2-(2-diethylaminoethoxy)benzoate, respectively.

Ethyl 4-(3-hydroxy-2,2-dimethylpropylamino)-2-[2-(2,6-dimethyl-1-piperidyl)ethoxy]benzoate was prepared following the above procedures but using 19 g. of ethyl 4-amino-2-[2-(2,6-dimethyl-1-piperidyl)ethoxy]benzoate, 7.32 g. of 3-hydroxy-2,2-dimethylpropanal, 15.5 g. of zinc dust, 14.5 g. of glacial acetic acid and 500 ml. of dry benzene. The resulting product, a pale yellow mobile oil, crystallized when triturated. The crystalline material was recrystallized twice from benzene, with decolorization using decolorizing charcoal, yielding ethyl 4-(3-hydroxy-2,2-dimethylpropylamino)-2-[2-(2,6-dimethyl-1-piperidyl)ethoxy]benzoate, M. P. 90.0-91.0° C. (cor.) [dried in vacuo at 65° C.].

Anal.—Calcd. for $C_{23}H_{38}N_2O_4$: C, 67.94; H, 9.42; N_D, 6.89. Found: C, 63.06; H, 9.31; N_D, 6.81.

Alternatively, the foregoing reductive alkylations can be carried out using, in place of zinc dust and glacial acetic acid, hydrogen under pressure in the presence of a hydrogenation catalyst such as platinum.

Other lower alkyl 4-alkylamino- or 4-hydroxyalkylamino-2-(tertiaryaminoalkoxy)benzoates which can be prepared according to the above procedures using the appropriate alkanal or hy-

droxyalkanal and lower alkyl 4-amino-2-(tertiaryaminoalkoxy)benzoate include the following: ethyl 4-n-butylamino-2-(2-dimethylamino-1-propoxy)benzoate; isobutyl 4-n-propylamino-2-[3-(1-pyrrolidyl)propoxy]benzoate; ethyl 4-(3-hydroxypropylamino)-2-[2-(2,5-dimethyl-1-pyrrolidyl)ethoxy]benzoate; methyl 4-n-hexylamino-2-(4-dimethylaminobutoxy)benzoate; n-propyl 4-n-amylamino-2-[2-di-n-butylamino]ethoxy]benzoate; n-butyl 4-n-butylamino-2-[3-(4-methyl-1-piperidyl)propoxy]benzoate; n-hexyl 4-n-propylamino-2-[2-(3-ethyl-1-piperidyl)ethoxy]benzoate; n-amyl 4-(5-hydroxyamylamino)-2-[3-(2-methyl-1-pyrrolidyl)propoxy]benzoate; and the like.

Alternatively, the lower alkyl 4-alkylamino- and 4-hydroxyalkylamino-2-(tertiaryaminoalkoxy)benzoates of our invention can be prepared by direct alkylation of the corresponding 4-amino compounds. This mode of alkylation is illustrated by heating ethyl 4-amino-2-(2-diethylaminoethoxy)benzoate with methyl iodide, ethyl bromide, 2-hydroxyethyl bromide, n-propyl iodide, n-butyl bromide or 5-hydroxypentyl chloride in the presence of a hydrogen halide acceptor such as potassium carbonate to yield, respectively, ethyl 4-methylamino-2-(2-diethylaminoethoxy)benzoate, ethyl 4-ethylamino-2-(2-diethylaminoethoxy)benzoate, ethyl 4-(2-hydroxyethylamino)-2-(2-diethylaminoethoxy)benzoate, ethyl 4-n-propylamino-2-(2-diethylaminoethoxy)benzoate, ethyl 4-n-butylamino-2-(2-diethylaminoethoxy)benzoate or ethyl 4-(5-hydroxyamylamino)-2-(2-diethylaminoethoxy)benzoate.

(4) *Lower alkyl 4-nitro-2-(tertiaryaminoalkoxy)benzoate quaternary ammonium salts*

These compounds are prepared by treating the corresponding lower alkyl 4-nitro-2-(tertiaryaminoalkoxy)benzoates with an alkyl or benzyl ester of an inorganic or organic acid of the type described hereinabove. The reaction is illustrated by the following examples.

Ethyl 4-nitro-2-(2-diethylaminoethoxy)benzoate methiodide was prepared as follows: To a solution of 6 g. of ethyl 4-nitro-2-(2-diethylaminoethoxy)benzoate in 50 ml. of ethyl acetate was added 15 ml. of methyl iodide. After about five minutes at room temperature, the mixture turned cloudy. It was then refluxed for one and one-half hours to ensure completion of the reaction. After about five minutes of refluxing, crystals formed and the color of the reaction mixture changed from deep orange to very pale yellow. The reaction mixture was cooled in ice, filtered and the product was washed with ethyl acetate. This material was recrystallized once from isopropanol-ethyl acetate and once from isopropanol alone, yielding ethyl 4-nitro-2-(2-diethylaminoethoxy)benzoate methiodide, M. P. 143.1-144.6° C. (cor.).

Anal.—Calcd. for $C_{16}H_{25}N_2O_5$: C, 42.49; H, 5.57; N_D, 6.20; I, 28.06. Found: C, 42.63; H, 5.46; N_D, 6.16; I, 28.15.

When the above procedure is followed but using, in place of methyl iodide, methyl bromide, ethyl chloride, n-propyl iodide, benzyl chloride or ethyl para-toluenesulfonate, there is obtained, respectively, ethyl 4-nitro-2-(2-diethylaminoethoxy)benzoate methobromide, ethyl 4-nitro-2-(2-diethylaminoethoxy)benzoate ethochloride, ethyl 4-nitro-2-(2-diethylaminoethoxy)benzoate n-propiodide, ethyl 4-nitro-2-(2-diethylaminoethoxy)benzoate benzochloride or ethyl 4-nitro-

2-(2-diethylaminoethoxy)benzoate etho - para-toluenesulfonate.

Ethyl 4-nitro-2-[3-(1-piperidyl)propoxylbenzoate methiodide was prepared as follows: Ten grams of ethyl 4-nitro-2-[3-(1-piperidyl)propoxylbenzoate hydrochloride was dissolved in about 150 ml. of water and the solution was treated with an excess of sodium bicarbonate. The mixture was saturated with sodium chloride and the oil that separated was extracted with ethyl acetate. The ethyl acetate extract was dried over anhydrous calcium sulfate, concentrated to a volume of about 125 ml., cooled and treated with 15 ml. of methyl iodide, whereupon precipitation took place slowly. To ensure completion of the reaction, the mixture was refluxed for thirty minutes, cooled and filtered; and the product was washed with ethyl acetate. One recrystallization from absolute ethanol yielded ethyl 4-nitro-2-[3-(1-piperidyl)propoxylbenzoate methiodide, M. P. 166.9-167.9° C. (cor.).

Anal.—Calcd. for $C_{18}H_{27}IN_2O_5$: I, 26.53; N_{NO_2} , 2.93. Found: I, 26.30; N_{NO_2} , 2.99.

n-Butyl 4-nitro-2-(2-diethylaminoethoxy)benzoate methiodide was prepared following the procedure described above for the preparation of ethyl 4-nitro-2-[3-(1-piperidyl)propoxylbenzoate methiodide but using 10 g. of n-butyl 4-nitro-2-(2-diethylaminoethoxy)benzoate hydrochloride, 15 ml. of methyl iodide and 125 ml. of ethyl acetate. This methiodide melted at 118.2-120.3° C. (cor.) when recrystallized from absolute ethanol-absolute ether.

Anal.—Calcd. for $C_{18}H_{29}IN_2O_5$: I, 26.42; N_{NO_2} , 2.92. Found: I, 26.30; N_{NO_2} , 3.11.

Additional lower alkyl 4-nitro-2-(tertiary-aminoalkoxy)benzoate methiodides prepared according to the above described procedure are given in Table III'.

Additional lower alkyl 4-nitro-2-(tertiary-aminoalkoxy)benzoate methiodides which can be prepared according to the foregoing procedure include the following: ethyl 4-nitro-2-(2-diethylamino-1-propoxy)benzoate methiodide; isobutyl 4-nitro-2-[3-(1-pyrrolidyl)propoxy]benzoate methiodide; ethyl 4-nitro-2-[2-(2,5-

dimethyl-1-pyrrolidyl)ethoxy]benzoate methiodide; methyl 4-nitro-2-(4-diethylaminobutoxy)benzoate methiodide; n-propyl 4-nitro-2-[2-(di-n-butylamino)ethoxy]benzoate methiodide; n-butyl 4-nitro-2-[3-(4-methyl-1-piperidyl)propoxy]benzoate methiodide; n-hexyl 4-nitro-2-[2-(3-ethyl-1-piperidyl)ethoxy]benzoate methiodide; n-amyl 4-nitro-2-[3-(2-methyl-1-pyrrolidyl)propoxy]benzoate methiodide; and the like.

(5) Lower alkyl 4-amino-2-(tertiary-aminoalkoxy)benzoate quaternary ammonium salts

These compounds are prepared preferably by reducing the above described lower alkyl 4-nitro-2-(tertiary-aminoalkoxy)benzoate quaternary ammonium salts. The reduction was carried out preferably by catalytic hydrogenation methods, as illustrated by the following examples.

Ethyl 4-amino-2-(2-diethylaminoethoxy)benzoate methiodide was prepared as follows: Ethyl 4-nitro-2-(2-diethylaminoethoxy)benzoate methiodide (18.5 g.) was mixed with 400 mg. of platinum oxide monohydrate and enough absolute ethanol to bring the total volume to 150 ml., and was treated with hydrogen under pressure at room temperature. The reaction took about fifteen minutes. The catalyst was filtered off and washed with absolute ethanol. The combined filtrate and washings were taken to dryness in vacuo and the residue was treated with ethyl acetate and the ethyl acetate was removed by distilling in vacuo. The residue was again treated with ethyl acetate and the solvent again removed in vacuo, thereby yielding a crystalline residue. This was filtered and washed well with ethyl acetate. This material was then recrystallized twice with decolorization, using decolorizing charcoal, once from isopropanol-ethyl ace-

tate and once from acetone. The resulting product, ethyl 4-amino-2-(2-diethylaminoethoxy)benzoate methiodide, melted at 139.2-141.1° C. (cor.).

Anal.—Calcd. for $C_{18}H_{27}IN_2O_3$: C, 45.50; H, 6.45; I, 30.05. Found: C, 45.28; H, 6.58; I, 29.70.

When the above procedure is followed but us-

ing, in place of ethyl 4-nitro-2-(2-diethylaminoethoxy)benzoate methiodide, ethyl 4-nitro-2-(2-diethylaminoethoxy)benzoate methobromide, ethyl 4-nitro-2-(2-diethylaminoethoxy)benzoate ethochloride, ethyl 4-nitro-2-(2-diethylaminoethoxy)benzoate n-propiopide, ethyl 4-nitro-2-(2-diethylaminoethoxy)benzoate benzochloride or ethyl 4-nitro-2-(2-diethylaminoethoxy)benzoate etho-para-toluenesulfonate, there is obtained, re-

solute ethanol. The resulting product melted at 83.2-92.4° C. when recrystallized three times from isopropanol.

Anal.—Calcd. for $C_{18}H_{31}IN_2O_3$: I, 28.18; N_D , 6.22. Found: I, 28.00; N_D , 6.33.

Additional lower alkyl 4-amino-2-(tertiary-aminoalkoxy)benzoate methiodides prepared according to the above procedure are given in Table IV.

^c NC_2H_8O =4-morpholinyl.

spectively, ethyl 4-amino-2-(2-diethylaminoethoxy)benzoate methobromide, ethyl 4-amino-2-(2-diethylaminoethoxy)benzoate ethochloride, ethyl 4-amino-2-(2-diethylaminoethoxy)benzoate n-propiopide, ethyl 4-amino-2-(2-diethylaminoethoxy)benzoate benzochloride or ethyl 4-amino-2-(2-diethylaminoethoxy)benzoate etho-para-toluenesulfonate.

Ethyl 4-amino-2-[3-(1-piperidyl)propoxy]benzoate methiodide was prepared as follows: A mixture containing 5 g. of ethyl 4-nitro-2-[3-(1-piperidyl)propoxy]benzoate methiodide, 200 mg. of platinum oxide monohydrate and 150 ml. of absolute ethanol was heated to 50° and was treated with hydrogen under pressure for one hour. The catalyst was filtered off and the filtrate was taken to dryness under reduced pressure. Ethyl acetate was added to the remaining material and the resulting solution was taken to dryness under reduced pressure. The material that remained crystallized when triturated with isopropanol. Three recrystallizations of this material from absolute ethanol yielded, ethyl 4-amino-2-[3-(1-piperidyl)propoxy]benzoate methiodide, M. P. 150.1-150.6° C. (cor.).

Anal.—Calcd. for $C_{18}H_{29}IN_2O_3$: I, 28.31; N_D , 6.25. Found: I, 28.61; N_D , 6.09.

When the foregoing procedure is followed but using ethyl 4-nitro-2-[3-(2-methyl-1-piperidyl)propoxy]benzoate methiodide in place of ethyl 4-nitro-2-[3-(1-piperidyl)propoxy]benzoate methiodide, there is obtained ethyl 4-amino-2-[3-(2-methyl-1-piperidyl)propoxy]benzoate methiodide.

n-Butyl 4-amino-2-(2-diethylaminoethoxy)benzoate methiodide was prepared according to the procedure described in the preceding example but using 5.0 g. of n-butyl 4-nitro-2-(2-diethylaminoethoxy)benzoate methiodide, 200 mg. of platinum oxide monohydrate and 150 ml. of ab-

Additional lower alkyl 4-amino-2-(tertiary-aminoalkoxy)benzoate methiodides which can be prepared according to the foregoing procedure include the following: ethyl 4-amino-2-(2-diethylamino-1-propoxy)benzoate methiodide; isobutyl 4-amino-2-[3-(1-pyrrolidyl)propoxy]benzoate methiodide; ethyl 4-amino-2-[2-(2,5-dimethyl-1-pyrrolidyl)ethoxy]benzoate methiodide; methyl 4-amino-2-(4-dimethylaminobutoxy)benzoate methiodide; n-propyl 4-amino-2-[2-(di-n-butylamino)ethoxy]benzoate methiodide; n-butyl 4-amino-2-[3-(4-methyl-1-piperidyl)propoxy]benzoate methiodide; n-hexyl 4-amino-2-[2-(3-ethyl-1-piperidyl)ethoxy]benzoate methiodide; n-amyl 4-amino-2-[3-(2-methyl-1-pyrrolidyl)propoxy]benzoate methiodide; and the like.

(6) *Lower alkyl 4-alkylamino- and 4-hydroxyalkylamino-2-(tertiary-aminoalkoxy)benzoate quaternary ammonium salts*

These compounds where the 4-alkyl or 4-hydroxyalkyl radical, designated hereinabove as R_2 , have from three to six carbon atoms are prepared preferably by reductively alkylating the corresponding lower alkyl 4-amino-2-(tertiary-aminoalkoxy)benzoate quaternary ammonium salts with hydrogen under pressure and an alkanal or a hydroxyalkanal having three to six carbon atoms, in the presence of a hydrogenation catalyst. This preparation and the products obtained thereby are illustrated by the following examples.

Ethyl 4-n-butylamino-2-(diethylaminoethoxy)benzoate methiodide can be prepared as follows: A mixture of 10 g. of ethyl 4-amino-2-(diethylaminoethoxy)benzoate methiodide, 5 g. of n-butanal (n-butylaldehyde), 0.5 g. of platinum oxide monohydrate and 150 ml. of absolute ethanol is treated at 50° C. with hydrogen under pressure until hydrogen is no longer taken up. The catalyst is filtered off and the filtrate is dis-

tilled in vacuo to remove the ethanol, thereby leaving the product, ethyl 4-n-butylamino-2-(diethylaminoethoxy)benzoate methiodide.

Following the above procedure but using 4-hydroxybutanal in place of n-butanal the resulting product obtained is ethyl 4-(4-hydroxybutylamino)-2-(2-diethylaminoethoxy)benzoate methiodide.

When the above procedure is followed but using, in place of ethyl 4-amino-2-(2-diethylaminoethoxy)benzoate methiodide, the corresponding ethyl 4-amino-2-(2-diethylaminoethoxy)benzoate methobromide, ethochloride, n-propiodide, benzochloride or etho-para-toluenesulfonate, there is obtained, respectively, ethyl 4-n-butylamino-2-(2-diethylaminoethoxybenzoate methobromide, ethyl 4-n-butylamino-2-(2-diethylaminoethoxy)benzoate ethochloride, ethyl 4-n-butylamino-2-(2-diethylaminoethoxy)benzoate n-propiodide, ethyl 4-n-butylamino-2-(2-diethylaminoethoxy)benzoate benzochloride or ethyl 4-n-butylamino-2-(2-diethylaminoethoxy)benzoate etho-para-toluenesulfonate.

When the above procedure is followed but using, in place of ethyl 4-amino-2-(2-diethylaminoethoxy)benzoate methiodide, ethyl 4-amino-2-[3-(1-piperidyl)propoxyl]benzoate methiodide, ethyl 4-amino-2-[3-(2-methyl-1-piperidyl)propoxyl]benzoate methiodide, n-butyl 4-amino-2-(2-diethylaminoethoxy)benzoate methiodide, ethyl 4-amino-2-[2-(2,6-dimethyl-1-piperidyl)ethoxy]benzoate methiodide, ethyl 4-amino-2-[3-(4-morpholinyl)propoxyl]benzoate methiodide, ethyl 4-amino-2-(2-dimethylaminoethoxy)benzoate methiodide or methyl 4-amino-2-(2-diethylaminoethoxy)benzoate methiodide, and using the appropriate respective alkanal or hydroxyalkanal, there is obtained, respectively, ethyl 4-n-propylamino-2-[3-(1-piperidyl)propoxyl]benzoate methiodide, 40 ethyl 4-n-amylamino-2-[3-(2-methyl-1-piperidyl)propoxyl]benzoate methiodide, n-butyl 4-n-hexylamino-2-(2-diethylaminoethoxy)benzoate methiodide, ethyl 4-(5-hydroxyamylamino)-2-[2-(2,6-dimethyl-1-piperidyl)ethoxy]benzoate methiodide, ethyl 4-(3-hydroxybutylamino)-2-[3-(4-morpholinyl)propoxyl]benzoate methiodide, ethyl 4-n-butylamino-2-(2-dimethylaminoethoxy)benzoate methiodide or methyl 4-(4-hydroxybutylamino)-2-(2-diethylaminoethoxy)benzoate methiodide.

Alternatively, the lower alkyl 4-alkylamino- and 4-hydroxyalkylamino-2-(tertiary-amino-alkoxy)benzoate quaternary ammonium salts can be prepared by treating the corresponding lower alkyl 4-alkylamino- or 4-hydroxyalkylamino-2-(tertiary-aminoalkoxy)benzoate with an alkyl or benzyl ester of an inorganic or organic acid of the type described hereinabove. This mode of preparation is illustrated by treating isobutyl 4-methylamino-2-(2-diethylaminoethoxy)benzoate, n-propyl 4-ethylamino-2-(2-diethylaminoethoxy)benzoate or ethyl 4-(2-hydroxyethylamino)-2-(2-diethylaminoethoxy)benzoate with methyl iodide to yield, respectively, isobutyl 4-methylamino-2-(2-diethylaminoethoxy)benzoate methiodide, n-propyl 4-ethylamino-2-(2-diethylaminoethoxy)benzoate methiodide or ethyl 4-(2-hydroxyethylamino)-2-(2-diethylaminoethoxy)benzoate methiodide.

Additional lower alkyl 4-alkylamino- and 4-hydroxyalkylamino-2-(tertiary-aminoalkoxy)benzoate methiodides which can be prepared according to the foregoing procedure include the following: ethyl 4-n-butylamino-2-(2-dimeth-

ylamino-1-propoxy)benzoate methiodide; isobutyl 4-n-butylamino-2-[3-(1-pyrrolidyl)propoxy]benzoate methiodide; ethyl 4-(6-hydroxyhexylamino)-2-[2-(2,5-dimethyl-1-pyrrolidyl)ethoxy]benzoate methiodide; methyl 4-(3-hydroxy-1-butylamino)-2-(4-dimethylaminobutoxy)benzoate methiodide; n-propyl 4-(3-hydroxypropylamino)-2-[2-(di-n-butylamino)ethoxy]benzoate methiodide; n-butyl 4-n-propylamino-2-[3-(4-methyl-1-piperidyl)propoxy]benzoate methiodide; n-hexyl 4-isobutylamino-2-[2-(3-ethyl-1-piperidyl)ethoxy]benzoate methiodide; n-amyl 4-n-hexylamino-2-[3-(2-methyl-1-pyrrolidyl)propoxy]benzoate methiodide; and the like.

We claim:

1. A quaternary ammonium salt having the formula

where Z is a member of the group consisting of nitro, amino, alkylamino and hydroxyalkylamino, X is a lower alkylene radical whose two free valence bonds are on different carbon atoms, NRR2 is a member of the group consisting of lower dialkylamino, 1-piperidyl, (lower alkylated)-1-piperidyl, 1-pyrrolidyl, (lower alkylated)-1-pyrrolidyl and morpholinyl, R2 is a lower alkyl radical, R4 is a member of the group consisting of a lower alkyl radical and a benzyl radical, and An is a non-toxic anion of a strong acid.

2. A quaternary ammonium salt of a lower alkyl 4-amino-2-(dialkylaminoalkoxy)benzoate having the formula

where X is a lower alkylene radical whose two free valence bonds are on different carbon atoms, R2 is a lower alkyl radical, R4 is a lower alkyl radical and An is a non-toxic anion of a strong acid.

3. A quaternary ammonium salt of a lower alkyl 4-amino-2-(diethylaminoalkoxy)benzoate having the formula

where X is a lower alkylene radical whose two free valence bonds are on different carbon atoms, R2 is a lower alkyl radical, R4 is a lower alkyl radical and An is a non-toxic anion of a strong acid.

4. A quaternary ammonium salt of a lower

23

alkyl 4-amino-2-(tertiary-aminoalkoxy) benzoate having the formula

where X is a lower alkylene radical whose two free valence bonds are on different carbon atoms, R_2 is a lower alkyl radical, NRR_1 is a 1-piperidyl radical, R_4 is a lower alkyl radical and An is a non-toxic anion of a strong acid.

5. A quaternary ammonium salt of an ethyl 4-amino-2-(dialkylaminoalkoxy) benzoate having the formula

where X is a lower alkylene radical whose two free valence bonds are on different carbon atoms, R_4 is a lower alkyl radical and An is a non-toxic anion of a strong acid.

6. A quaternary ammonium salt of an ethyl 4-amino-2-(diethylaminoalkoxy) benzoate having the formula

where X is a lower alkylene radical whose two free valence bonds are on different carbon atoms, R_4 is a lower alkyl radical and An is a non-toxic anion of a strong acid.

7. Ethyl 4 - amino - 2 - (2 - diethylaminoethoxy) benzoate methiodide.

8. A process of preparing a quaternary ammonium salt of a lower alkyl 4-amino-2-(tertiary-aminoalkoxy) benzoate having the formula

where X is a lower alkylene radical whose two free valence bonds are on different carbon atoms, NRR_1 is a member of the group consisting of lower dialkylamino, 1-piperidyl, (lower alkylated)-1-piperidyl, 1-pyrrolidyl, (lower alkylated)-1-pyrrolidyl and morpholinyl, R_2 is a lower alkyl radical, R_4 is a member of the group consisting of a lower alkyl radical and a benzyl radical and An is a non-toxic anion of a strong acid, which comprises treating the corresponding lower alkyl 4 - nitro - 2 - (tertiary-aminoalkoxy) benzoate with an ester having the formula R_4-An and treating the resulting lower alkyl 4-nitro-2-(tertiary-aminoalkoxy) benzoate quaternary ammonium salt with a reducing agent effective to reduce nitro groups to amino groups.

9. A process of preparing a quaternary ammonium salt of a lower alkyl 4-amino-2-(dialkylaminoalkoxy) benzoate having the formula

24

where X is a lower alkylene radical whose two free valence bonds are on different carbon atoms, R_2 is a lower alkyl radical, R_4 is a lower alkyl radical and An is a non-toxic anion of a strong acid, which comprises treating the corresponding lower alkyl 4-nitro-2-(dialkylaminoalkoxy) benzoate with an ester having the formula R_4-An and treating the resulting lower alkyl 4-nitro-2-(dialkylaminoalkoxy) benzoate quaternary ammonium salt with a reducing agent effective to reduce nitro groups to amino groups.

10. A process of preparing a quaternary ammonium salt of a lower alkyl 4-amino-2-(diethylaminoalkoxy) benzoate having the formula

where X is a lower alkylene radical whose two free valence bonds are on different carbon atoms, R_2 is a lower alkyl radical, R_4 is a lower alkyl radical and An is a non-toxic anion of a strong acid, which comprises treating the corresponding lower alkyl 4-nitro-2-(diethylaminoalkoxy) benzoate with an ester having the formula R_4-An and treating the resulting lower alkyl 4-nitro-2-(diethylaminoalkoxy) benzoate quaternary ammonium salt with a reducing agent effective to reduce nitro groups to amino groups.

11. A process of preparing a quaternary ammonium salt of a lower alkyl 4-amino-2-(tertiary-aminoalkoxy) benzoate having the formula

where X is a lower alkylene radical whose two free valence bonds are on different carbon atoms, R_2 is a lower alkyl radical, NRR_1 is a 1-piperidyl radical, R_4 is a lower alkyl radical and An is a non-toxic anion of a strong acid which comprises treating the corresponding lower alkyl 4-nitro-2-(tertiary-aminoalkoxy) benzoate with an ester having the formula R_4-An and treating the resulting lower alkyl 4-nitro-2-(tertiary-aminoalkoxy) benzoate quaternary ammonium salt with a reducing agent effective to reduce nitro groups to amino groups.

12. A process of preparing a quaternary ammonium salt of ethyl 4-amino-2-(dialkylaminoalkoxy) benzoate having the formula

where $\mathbf{X}$ is a lower alkylene radical whose two free valence bonds are on different carbon atoms, $\mathbf{R}_4$ is a lower alkyl radical and $\mathbf{A}^-$ is a non-toxic anion of a strong acid, which comprises treating the corresponding ethyl 4 - nitro - 2 - (dialkylaminoalkoxy) benzoate with an ester having the formula $\mathbf{R}_4\text{-A}^-$ and treating the resulting ethyl 4-nitro-2-(dialkylaminoalkoxy) benzoate quaternary ammonium salt with a reducing agent effective to reduce nitro groups to amino groups.

13. A process of preparing a quaternary ammonium salt of ethyl 4-nitro-2-(diethylaminoalkoxy) benzoate having the formula

where $\mathbf{X}$ is a lower alkylene radical whose two free valence bonds are on different carbon atoms, $\mathbf{R}_4$ is a lower alkyl radical and $\mathbf{A}^-$ is a non-toxic

anion of a strong acid, which comprises treating the corresponding ethyl 4 - nitro - 2 - (diethylaminoalkoxy) benzoate with an ester having the formula $\mathbf{R}_4\text{-A}^-$ and treating the resulting ethyl 4-nitro-2-(diethylaminoalkoxy) benzoate quaternary ammonium salt with a reducing agent effective to reduce nitro groups to amino groups.

14. A process of preparing ethyl 4-nitro-2-(2-diethylaminoethoxy)benzoate methiodide, which comprises treating ethyl 4-nitro-2-(2-diethylaminoethoxy)benzoate with an ester having the formula $\mathbf{R}_4\text{-A}^-$ and treating the resulting ethyl 4-nitro-2-(2-diethylaminoethoxy)benzoate methiodide with a reducing agent effective to reduce nitro groups to amino groups.

15. Ethyl 4-amino-2-[2-(1-piperidyl)ethoxy]-benzoate methiodide.
